UNITED STATES PATENT OFFICE.

JOHN SABO, OF CLEVELAND, OHIO.

MOTOR-CYCLE LOCK.

1,121,405.

Specification of Letters Patent. Patented Dec. 15, 1914.

Application filed October 9, 1912. Serial No. 724,870.

To all whom it may concern:

Be it known that I, JOHN SABO, a citizen of the United States, and resident of Cleveland, in the county of Cuyahoga and State 5 of Ohio, have invented certain new and useful Improvements in Motor-Cycle Locks, of which I hereby declare the following to be a full, clear, and exact description, such as will enable others skilled in the art to which it 10 appertains to make and use the same.

The objects of the invention are to provide a simple portable and efficient device for clamping the standard upon which a motor 15 cycle or other vehicle is supported to the frame, so that it will be impossible for any one to propel the machine on its tires or to use it and hence the danger of its being 20 stolen is practically obviated since the weight of the machine would ordinarily prevent it from being carried away.

The swinging standard on which the rear extremity of the machine rests is ordinarily provided with a socket or fork and the lower bar of the motor cycle with a projection 25 which rests in the socket when the swinging standard is in place.

The present invention includes means for rigidly attaching these parts together so that the standard on which the machine rests 30 cannot be removed except by the use of a key.

The invention comprises the combination and arrangement of means for clamping the frame of the motor cycle and the standard 35 together and includes a locking clasp therefor, and the construction of details as hereinafter described, shown in the accompanying drawings and specifically pointed out in the claims.

40 In the accompanying drawings Figure 1 is a side elevation showing portions of the lower bar of the motor cycle and of the standard provided with a supporting bracket and parts rigidly secured together; Fig. 2 is 45 a perspective view of the lower bar and bracket showing the means for detachably securing them together; Fig. 3 is a vertical central section through the bar, bracket and locking device, showing the use of the pad lock. Figs. 4 and 5 are side and edge views 50 respectively of the locking device; Fig. 6 is a side elevation of the upper portion of the bracket.

In these views A is a rigid portion of the 55 frame of the motor cycle, B is one leg of the support which swings on the center C. To

this leg is rigidly secured the bracket D having a fork or socket D' in its upper extremity. Upon the bar A is secured a short projection E which is provided with a flanged 60 outer extremity E' and the fork D' rests against the projection E and is prevented from sliding off the end of the projection by means of said flange.

To secure the parts closely together a 65 clamp F having an eye F' is set over the projection E. This eye is elongated at the lower end to inclose the projecting sides of the fork D', which is provided with a ribbed portion D² to permit of this action. A rib 70 D³ extends longitudinally of the bracket D connecting with the rib D².

The clamp F is provided with a longitudinal slot F² in which the longitudinal rib D³ of the bracket lies. The eye at the inner and 75 upper edge of the clamp is enlarged at F³ permitting the lower end to be tilted forward when placing the clamp in position and when removing the same, from the flanged projection E'. 80

When in parallel position with the bracket it will be seen that a cross bar F⁴ integral with the sides of the clamp secures the extremities of the clamp together so that they cannot be spread apart to remove the clamp 85 and fits down closely over the bracket. To prevent removing the clamp a padlock or ordinary bicycle chain lock G or other locking clasp is secured over the bracket and sides of the clamp and is placed below the 90 center of the clamp to prevent the lower ends of the clamp from being moved outwardly so as to release the eye of the clamp from the projection.

To prevent the locking clasp from slipping 95 down and off from the sides of the clamp, ribs F⁵ F⁶ are employed to retain it in place. The clamp can be removed in only one way, by tilting it outwardly at the bottom until the lower edge of the eye has passed by the 100 rib on the fork, when the upper edge can be lifted over the flange E'.

The eye portion of the clamp retains the projection and fork in close engagement and the sides of the longitudinal slot grasp the 105 rib on the bracket on both sides and prevent lateral movement.

The device is easily attached and being of small size is readily carried in the pocket. It can readily be adapted to all styles of 110 auto-cycles or other vehicles and supports therefor and any modifications in form or

shape can be made which are included within the scope of the claims.

Having described the invention what I claim as new and desire to secure by Letters Patent is:

1. A device for detachably securing the frame of a vehicle and a standard together, said frame and standard having projections engaging each other, comprising a clamp 10 engaging said projections on said frame and standard simultaneously, and means for locking said clamp and standard together.
  2. A device for detachably securing the frame of a vehicle to a standard, said frame and standard having engaging parts, comprising a clamp having rigid members 15 enclosing said engaging parts of frame and standard, and a locking clasp adapted to prevent the removal of said clamp.
  3. In a detachable device for securing the frame of a vehicle to a standard, said frame and standard provided with adjacent projections, a member having an opening adapted to encircle said adjacent projections 20 and having an extension, and a locking clasp encircling said extension and a portion of said standard.
  4. In a detachable device for securing the frame of an auto cycle to a standard said 25 frame and standard provided with closely adjacent parts, a rigid device having an opening to be sleeved over said adjacent parts on frame and standard, a locking clasp adapted to secure said closely adjacent parts of frame and standard in said rigid device, and means for preventing the removal of 30 said locking clasp.
  5. In a detachable clamp for securing the adjacent parts of a frame of a vehicle and a 35 standard together, said frame and standard 40
- having closely engaging projections, an eye portion on said clamp adapted to inclose both said engaging projections, said clamp having an extension, a locking clasp encircling one of said adjacent parts and said extension, and means for preventing lateral movement of said extension.
6. In a detachable means for securing a frame member of a vehicle and a standard therefor together, said frame member having a projection flanged at its outer end, said standard provided with a ribbed fork adapted to engage said flanged projection on said frame, a rigid clamp having an opening adapted to encircle the flanged projection on said frame and said ribbed fork on said standard, said clamp provided also with an extension engaging the stem of said fork, and a locking clasp adapted to secure said extension removably to said stem.
7. In a detachable means for securing a member of a vehicle frame to a standard, said frame member having a flanged projection and said standard having a fork and a longitudinal rib, a rigid clamp longitudinally slotted and provided with an eye opening adapted to be sleeved over said flanged projection on one member and over said ribbed fork on the other member, the slot in said clamp adapted to engage the longitudinal rib on said fork, and a locking clasp adapted to encircle said fork and said clamp to retain the clamp in position.

In testimony whereof, I hereunto set my hand this 5th day of October 1912.

JOHN SABO.

In presence of—
ALEX. C. MACKENZIE,
WM. M. MONROE.
